US0D1015671S

(12) **United States Design Patent** (10) **Patent No.:** **US D1,015,671 S**
(45) **Date of Patent:** **** Feb. 20, 2024**

(54) **DRYING RACK**

(71) Applicant: **Honey-Can-Do International, LLC**,
Berkeley, IL (US)

(72) Inventors: **Kristina Tarasova**, Arlington Heights,
IL (US); **Pamela Mical**, Brookfield, IL
(US); **Jeffrey Bull**, Naperville, IL (US);
Daniel Tagtow, Austin, TX (US); **Steve
Greenspon**, Burr Ridge, IL (US); **Alex
Hrovat**, Lisle, IL (US)

(73) Assignee: **Honey-Can-Do International, LLC**,
Berkeley, IL (US)

(**) Term: **15 Years**

(21) Appl. No.: **29/815,590**

(22) Filed: **Nov. 15, 2021**

(51) LOC (14) Cl. **07-05**

(52) U.S. Cl. **D32/58**

(57) **CLAIM**

The drying rack, as shown and described.

DESCRIPTION

FIG. 1 is a front left side perspective view showing the new design for a drying rack;

FIG. 2 is a rear right side perspective view thereof;

FIG. 3 is a front left side perspective view thereof, from underneath the drying rack;

FIG. 4 is a rear right side perspective view thereof;

FIG. 5 is a front view thereof;

FIG. 6 is a rear view thereof;

FIG. 7 is a left side view thereof;

FIG. 8 is a right-side view thereof

FIG. 9 is a top plan view thereof; and,

FIG. 10 is a bottom plan view thereof.

1 Claim, 9 Drawing Sheets
